UNITED STATES PATENT OFFICE.

MABEL J. KAMPF, OF HOLLYWOOD, CALIFORNIA.

INNER DUST BAG FOR VACUUM CLEANERS.

Application filed October 20, 1924. Serial No. 744,809.

To all whom it may concern:

Be it known that I, MABEL J. KAMPF, a citizen of the United States, residing at Hollywood, in the county of Los Angeles and State of California, have invented new and useful Improvements in Inner Dust Bags for Vacuum Cleaners, of which the following is a specification.

This invention relates to improvements in 10 vacuum cleaners.

In the construction of the majority of vacuum cleaners, the air carrying dust and dirt is directed into a removable dust bag, in which the dust is collected. When the 15 dust bag is partially filled with dust and dirt, it is adapted to be removed from the cleaner and the dirt shaken therefrom. This operation is dirty and usually requires a considerable amount of shaking of the bag, and 20 consequent scattering of the dust and dirt results.

It is therefore an object of this invention to provide an inner dust bag or lining bag for the dust bag upon a vacuum cleaner, 25 which lining bag receives the dirt and dust; and upon removal of the lining bag from the dust bag upon the vacuum cleaner, the dust and dirt may easily and quickly be taken out with it.

30 A further object of this invention is to provide a lining bag for the dust bag upon vacuum cleaners which will be easily, simply and cheaply constructed so that the bags may be marketed for a reasonable amount 25 and may be destroyed after having been removed from the dust bag upon the vacuum cleaner.

With the foregoing and other objects in view which will be made manifest in the 40 following detailed description and pointed out in the appended claim, reference is had to the accompanying drawings for an illustrative embodiment of the invention, wherein:

45 Figure 1 is a side elevation of a vacuum cleaner to which the improved lining bag has been applied, the dust bag and the lining bag being shown in section;

Fig. 2 is a top plan view of the improved 50 lining bag; and

Fig. 3 is a side elevation of the lining bag, parts being shown in section.

Referring to the accompanying drawings wherein similar reference characters designate similar parts throughout, the vacuum 55 cleaner, generally designated at 10, which

is mounted upon wheels 11, may be of any conventional construction. As is customary with many vacuum cleaners, a pivoted handle 12 is provided which is adapted to support the upper end of a dust bag 13 by means of a spring 14, or an equivalent flexible element.

The dust bag 13 is usually formed of a closely woven fabric and is provided with 60 a collar 15 secured about its neck, which collar is provided with a flange 17 which is a companion to the flange 18 formed upon the cleaner body. The dust bag 13 is secured to the cleaner 10 by securing together 65 the companion flanges 17 and 18, as indicated at 19. When the dust bag 13 has been filled with dirt and dust, the fastening means, indicated at 19, may be removed and the dust 70 may be poured out of the neck of the dust 75 bag 13.

An improvement over this construction resides in applying an inner bag indicated at 20, which bag may be formed of paper or similar material and may be formed in any 80 suitable manner to provide a reduced neck 21 and a tapered closed end 22. A ring 23 of relatively stiff cardboard is secured to the neck 21 of the bag 20 by passing the neck through the ring and having the edges 85 of the neck glued or otherwise secured to the ring 23. As shown in Fig. 1, the ring 23 provides an annular flange upon the neck of the bag, which flange is adapted to be retained between the companion flanges 17 90 and 18. The air entering the dust bag 13 and the lining bag 20 has the dust removed therefrom and retained in the lining bag 20. The porosity of the paper of which the bag 95 is made, or of any other material suitable for this construction, permits the air entering the bag to pass therethrough and through the fabric dust bag 13.

When the lining bag 20 has been filled or 100 partially filled with dirt, the companion flanges 17 and 18 may be unfastened from each other and the lining bag 20 may be removed, carrying with it the dust and dirt retained therein. This permits the dust bag 13 to be easily and quickly cleaned. Because of the cheapness of the material of 105 which the lining bag 20 is constructed, the lining bag with the dirt therein may be destroyed and a new lining bag may be used within the dust bag 13 upon further use of 110 the vacuum cleaner.

It is seen that the lining bag accomplishes

a number of useful results, residing in easily and quickly cleaning the dust bag 13 without shaking or scattering the dust and dirt therein. The tapered end 22 of the lining bag is so formed that this end may accommodate itself so as to fit snugly within the upper end of the dust bag 13. The general shape of the bag 20 is so formed as to snugly fit against the interior surface of the fabric dust bag 13.

It will be understood that various changes in the detail of the construction may be made without departing from the spirit or scope of the invention as defined by the appended claim.

I claim:

In combination with the dust bag of a vacuum cleaner, a paper lining bag removably positioned in said dust bag, said lining bag having a tapered neck, and a ring 20 formed of relatively stiff material through which the neck on the bag extends, the edges of the neck on the bag being secured to the ring whereby the ring provides a relatively stiff flange on the neck of the bag adapted to 25 be positioned between the companion flanges on the dust bag and on the cleaner.

In testimony whereof I have signed my name to this specification.

MABEL J. KAMPF.
